UNITED STATES PATENT OFFICE.

HORATIO E. VAN DOREN, OF SOUTH BEND, INDIANA.

MOUNTING-BLOCK FOR EMBOSSED-DIES.

1,112,578.

Specification of Letters Patent.

Patented Oct. 6, 1914.

Application filed June 17, 1914. Serial No. 845,708.

To all whom it may concern:

Be it known that I, HORATIO E. VAN DOREN, a citizen of the United States, residing at South Bend, in the county of St. Joseph and State of Indiana, have invented certain new and useful Improvements in Mounting-Blocks for Embossing-Dies, of which the following is a specification.

The invention relates to an improvement in mounting blocks for embossing dies, being more particularly directed to a clamping block arranged for adjustable connection with the mounting block and for holding co-operation with the die, the die engaging means operating to lock the respective securing means against movement.

The present invention is primarily designed with a view to securing an embossing die to a mounting block of portable type to permit the use of ordinary presses for embossing; the die securing means being arranged with a particular view to provide for its adjustment on the block with respect to position, and to render such means automatically locking to prevent independent movement of the parts under any circumstances.

The invention in the preferred form of details will be described in the following specification, reference being had particularly to the accompanying drawings, in which:—

Figure 1 is a plan view illustrating the improvement. Fig. 2 is an enlarged plan of one of the clamping blocks. Fig. 3 is a forward end elevation of the clamping block. Fig. 4 is a side elevation of the same. Fig. 5 is a broken view in elevation, with the clamping block in section, illustrating the co-operative relation of the parts.

Referring particularly to the accompanying drawings, 1 represents a mounting block of any appropriate or desired form, the preferred type being of a portable character, and self-heating, in order that it might be used with any ordinary type of press. The die receiving surface of the block is formed throughout any appropriate or desired area with a series of regularly or irregularly arranged threaded openings 2, designed with a view to permitting the co-operation of the clamping block with such portion or portions of the mounting block as will position the die as desired.

55 The clamping block, of which there may

be any desired number used in accordance with the size of the die, comprises a block 3, of less thickness than the corresponding dimension of the embossing die 4, the block being of approximately rectangular form and having formed therein countersunk openings 5 interiorly threaded and arranged in alignment longitudinally of the block. The openings 5 are spaced apart a distance somewhat less than the spacing of the openings 2 whereby to provide an additional variation in adjustment, as will be obvious. The block is also formed with a longitudinally extending bore 6, interiorly threaded and opening through what will be herein-after termed the inner end of the block. The bore 6 is arranged centrally of the height of the block, and about mid-distance between its sides, the end corners of the block being preferably cut away for convenience.

The block is formed with a longitudinal extending incision or channel 7, the same being in the nature of a saw kerf and opening through the inner end of the block and through the side walls thereof. The kerf or channel 7 thus includes or intercepts the bore 6 and also the threaded openings 5, or in other words the block is threaded the forward portion thereof formed in effect of two sections, normally spaced a slight distance apart.

A holding screw 8 is designed for co-operation with the bore 6, being exteriorly threaded to fit said bore and being terminally pointed at 9 to engage the die block. In rear of the pointed end the holding screw is of angular formation in cross section as at 10, whereby to provide for manipulation of the screw in securing or releasing the die.

In use the clamp blocks are secured in proper relative positions beyond the contour of the die blocks 4 and screws 11 threaded through the approximate opening 5 in each block and into the underlying opening 2 in the die block. The clamping blocks are thus rigidly secured to the die block. The holding screws 8 are then adjusted longitudinally of the bore 6 until the pointed ends 9 thereof fix and rigidly hold the die 4, and with said die and clamp block rigidly held against movement, a further turning of the screw 8 will tend to cause the threads thereof to ride the threads of the bore 6. This has the effect of spreading the sections of

the block, that is slightly elevating the upper section with respect to the lower section. This operation will not only bind or lock the holding screw 8 against possibility of turning in the bore but will slightly offset one wall of the openings 5 with respect to the diametrical opposite portion of said wall, thereby binding the screws 11 in said openings against possibility of movement. It will thus be apparent that by means of the channels 7 I have provided an automatic locking means for both the die holding screw 8 and the block holding screws 11, insuring the positioning of the parts against possibility of movement in use.

Any appropriate number of clamp blocks may be used and by means of the formation of the mounting block, as described they may be adjusted in any relative positions, thereby providing for the use of any form of die and the disposition of such die in practically any place on the mounting block.

What is claimed is:

1. Means for securing dies on mounting blocks including a clamp block, means for securing the same to the mounting block, and an adjustable die engaging element carried by the clamp block adapted to automatically lock itself against independent movement with relation to said block.

2. A clamp block for securing dies on mounting blocks including a body formed with a threaded bore, a holding screw co-operating with said bore and designed to engage the die, and means for automatically locking said screw against movement.

3. A means for securing embossing dies on mounting blocks including a clamp block, means for securing the same to the mounting block, a holding screw carried by the clamp block and adapted to engage the die, and means operable in the adjustment of said holding screw to automatically lock the same against independent movement.

4. A mounting block, and die holding means thereon, including a die engaging holding screw, and means for automatically locking said screw in the movement thereof

subsequent to the engagement of the screw and die. 50

5. A clamp block for securing embossing dies on mounting blocks including a body, a holding screw having threaded connection with the body and adapted to engage the embossing die, said block being formed with a longitudinally extending channel dividing the bore for the holding screw. 55

6. A clamp block for securing embossing dies on holding blocks including a body formed with a longitudinally extending threaded bore, a vertically extended threaded opening and a longitudinal channel intercepting said bore and opening. 60

7. The combination with a mounting block form with a series of threaded openings of a clamp block having a threaded opening to register with any one of the threaded openings in the mounting block, said clamp block having a longitudinally threaded bore, and a channel extending longitudinally of 70 the block and intercepting said bore and opening.

8. The combination with a mounting block and an embossing die of a clamp block, means for securing said clamp block to the mounting block, means carried by the clamp block to engage the die, and means for simultaneously locking both of said previously mentioned means in the operation of the latter. 75

9. The combination with a mounting block and an embossing die of a clamp block, means for securing said clamp block to the mounting block, means carried by the clamp block to engage the die, and means for simultaneously locking both of said previously mentioned means, in the operation of the means for engaging the die in the operation of the latter. 85

In testimony whereof I affix my signature in presence of two witnesses.

HORATIO E. VAN DOREN.
